CLAIM

The ornamental design for a toothbrush and container set, as shown and described.

DESCRIPTION

FIG. 1 is a perspective view of a toothbrush and container set showing my new design;

FIG. 2 is a side elevational view thereof; the opposite side elevational view being a mirror image;

FIG. 3 is a top plan view thereof;

FIG. 4 is a bottom plan view thereof;

FIG. 5 is an elevational view as seen from the left of FIG. 3;

FIG. 6 is a right end elevational view thereof;

FIG. 7 is a perspective view thereof, shown with both toothbrushes projecting from the container portion; and FIG. 8 is a perspective view thereof, shown with both toothbrushes enclosed in the container portion.
